(57) CLAIM

The ornamental design for the game apparatus, as shown and described.

DESCRIPTION

FIG. 1 is a perspective view of the game apparatus according to the invention;

FIG. 2 is a front elevational view thereof;

FIG. 3 is a rear elevational view thereof;

FIG. 4 is a left side elevational view thereof, the right side being a mirror image;

FIG. 5 is a top plan view thereof with a partial enlarged view;

FIG. 6 is a bottom plan view thereof; and,

FIG. 7 is a partial perspective view of the game apparatus according to the invention.

The portions of the design shown in broken lines form no part of the claimed design.
